UNITED STATES PATENT OFFICE.

MARION FRANK WOOTEN, OF CHARLOTTE, NORTH CAROLINA.

**DESIGN FOR A PIN, BUTTON, BADGE, EMBLEM, INSIGNIA, MEDAL, WATCH-FOB, OR
ARTICLE OF SIMILAR NATURE.**

53,263.

Specification for Design.

Patented Apr. 29, 1919.

Application filed January 22, 1919. Serial No. 272,582. Term of patent 7 years.

To all whom it may concern:

Be it known that I, MARION F. WOOTEN, a citizen of the United States of America, residing at Charlotte, in the county of Mecklenburg and State of North Carolina, have invented a new, original, and ornamental Design for Pins, Buttons, Badges, Emblems, Insignia, Medals, Watch-Fobs, and Articles of Similar Nature, of which the following is

a specification, reference being had to the accompanying drawing, forming part hereof.

The figure is a view of the face of a pin showing my new design.

I claim:

The ornamental design for a pin, button, badge, emblem, insignia, medal, watch-fob, or article of similar nature, as shown.

MARION FRANK WOOTEN.
